INFLATED TOY FIGURE

Irvin J. Gershen, Springfield, N.J., assignor to Johnson
& Johnson, a corporation of New Jersey

Filed Dec. 21, 1965, Ser. No. 263

Term of patent 14 years

(Cl. D34—15)

FIG. 1.

FIG. 2.

FIG. 3.

FIG. 1 is a perspective view of an inflated toy figure showing my design; the side opposite FIG. 1 is substantially the same;

FIG. 2 is a front end view of the toy shown in FIG. 1; FIG. 3 is a back end view of the toy shown in FIG. 1.

I claim:

The ornamental design for an inflated toy figure, as shown and described.
